UNITED STATES PATENT OFFICE.

ROLLIN H. WHITE, OF CLEVELAND HEIGHTS, OHIO, ASSIGNOR TO THE CLEVELAND TRACTOR COMPANY, OF EUCLID, OHIO, A CORPORATION OF OHIO.

TRACTOR.

Application filed January 14, 1922. Serial No. 529,197.

To all whom it may concern:

Be it known that I, ROLLIN H. WHITE, a citizen of the United States, residing at Cleveland Heights, in the county of Cuyahoga and State of Ohio, have invented a certain new and useful Improvement in Tractors, of which the following is a full, clear, and exact description.

This invention relates to the class of tractors which have no main or motor supporting frame, except such as results from properly constructing and connecting together various castings whose primary functions are to house the motor and transmission and support the radiator and liquid containing tanks.

When a tractor has such a main frame it is necessary to devise new means for supporting various necessary adjunctive apparatus, which in the older and more common constructions were supported upon the same frame which also supported the motor and transmission mechanism housing.

The object of this invention is to provide a novel and efficient built up frame member of the character specified, of suitable form for the purpose, and to combine therewith in an effective and convenient manner such adjunctive appliances as the fuel tank, radiator housing, radiator, air purifier, etc.

The invention consists in the construction and combination of parts shown in the drawings, hereinafter described and pointed out definitely in the appended claims.

In the drawings,

Fig. 1 is a side elevation of the units assembled forming the frame.

Fig. 2 is a top plan view,

Fig. 3 is a partial cross sectional view taken on lines A-A of Fig. 1, illustrating the tank secured upon the cradle and the rear support for the cradle,

Fig. 4 is a view of the air purifier taken on lines B-B of Fig. 1, illustrating in cross section the connection with the cradle,

Fig. 5 is a front elevation of the frame taken on lines C-C of Fig. 1,

Fig. 6 is a fragmentary section taken on lines E-E of Fig. 1 showing the rear support for the cradle,

Fig. 7 is a longitudinal sectional view taken on lines D-D of Fig. 1 showing the radiator frame, the tanks, the air purifier and the cradle support.

The main frame includes in its construc-

tion a rear member 10 which is a hollow casting so constructed that the transmission mechanism may be mounted and enclosed therein. The rear end of this transmission case is formed with an opening, over which is bolted a removable cover plate 11, by the removal of which access may be had to the enclosed mechanism. The main frame also includes the casting 12 which comprises the engine cylinders and the greater part of the crank case of an internal combustion motor; it also includes a front gear case 13, which is a hollow member having a forwardly projecting shelf 14 at its lower end. The primary purpose of this front gear case is to support the radiator, the fan shaft, the pump and the magneto, and to house the gears by which motion is transmitted from the crank shaft to said parts, and to the cam shaft. These three frame members 10, 12 and 13 are castings and are flanged along their vertical meeting edges and are detachably connected together by bolts 15, which pass through the flanges. This frame also includes a bottom member 16 which closes the openings in the bottom of the transmission case 10, of the crank case casting 12, and of the gear case 13. This member 16 is preferably made of pressed metal with a flanged edge by means of which it may be removably secured by bolts 17 to the flanged lower edges of the three members 10, 12 and 13, which lower edges are preferably all in the same plane. This bottom member is not intended to support any of the motor mechanism or transmission mechanism, it merely serves as an oil container and a closure for the otherwise open bottoms of the parts to which it is secured, preventing the access of dirt and dust thereto. When it is removed, access for inspection or repair may be had to the mechanism which is supported within the three hollow members 10, 12 and 13.

Upon the forwardly projecting shelf 14 of the gear case is an open housing 18 rigidly secured thereto by bolts. This housing is an open channel frame, preferably made of riveted together pressed metal pieces having a rear reinforcing plate 18^a. The function of the housing is to house the radiator 19, and to provide a suitable front support for a built up cradle which is provided for the fuel tank 20 and the air purifier casing 21. A suitable cap 18^b having a rearwardly extending top portion encloses the radiator 110

within the housing and is secured to the housing by bolts 18^c.

The cradle includes two side angle bars 22, which at their front ends rest upon and are fixed by bolts 22^a to projecting angle bars 23 secured to the rear face of the plate 18^a on the radiator housing. A channel shaped standard 24 extends within the space between the upper portions of the transmission and engine castings, and the sides thereof which extend rearwardly of the transmission casting are detachably secured to the side walls thereof by bolts 25. The upper end 26 of the standard 24 extends at right angles thereto and serves as a support for the rear ends of the side bars which are detachably secured thereto by bolts 27.

The fuel tank 20 is shaped with a flat bottom which rests upon and is supported by the flanges of the side bars 22 of the cradle. Angle bars 28 are secured to the projecting sides of the tank and the depending portions thereof are detachably secured to the side bars by bolts 29.

25 The air purifier unit is supported upon the cradle behind the fuel tank and includes an air purifier casing 21 provided with plates 30, secured to opposite sides thereof and depending therefrom; the depending portion being spaced to fit outside of the side bars 22 of the cradle and being detachably secured thereto by bolts 31.

30 The rearwardly extending portion of the cap 18^b extends over the fuel tank 20 and 35 the air purifier housing 21 is in alignment with the fuel tank. These members extend over the engine and form a canopy therefor when assembled.

It will be readily understood that changes 40 in size, form and construction of various parts of my improved tractor may be made and substituted for those herein shown and described without departing from the spirit of my invention, the scope of which is set forth in the appended claims.

45 Having described my invention, I claim:—

1. A frame for tractors comprising a transmission case having an opening through its bottom, an engine unit including the crank case having an open bottom, and a front gear housing having an opening through its bottom, said case, unit, and housing being detachably secured rigidly together, and a pan secured to said parts 50 and closing the openings through their bottoms.

2. A frame for tractors comprising the following rigidly connected but separable parts, viz, a rear transmission case having 60 an opening through its bottom, an engine unit including the crank case having an open bottom, and a front gear housing having an opening through its bottom, said

three parts having their lower edges in the same horizontal plane, and a pan secured 65 to the lower edges of said three parts and closing the openings through their bottoms.

3. In a machine of the character specified, a main frame including an engine, a radiator housing fixed to said frame, a radiator within said housing, a rearwardly extending cap secured over said housing, a standard secured to said frame, a cradle fixed to said standard and said housing, a fuel 70 tank supported upon and fixed to said cradle, said cap extending over said tank and forming therewith a continuous canopy for the engine.

4. A frame for tractors comprising the 80 following rigidly connected but separable parts, viz, a rear transmission case having an opening through its bottom, an engine unit including the crank case having an open bottom, a front gear housing having 85 an opening through its bottom, and having a forwardly extended shelf adjacent its bottom, a pan secured to the lower edges of said three parts closing the openings through their bottoms, a radiator housing 90 fixed to the forwardly projecting shelf of the front gear case, a standard fixed to the said frame behind the engine, and a rigid cradle fixed to the radiator housing and to said standard and located in a plane above 95 the engine.

5. A frame for tractors comprising the following rigidly connected but separable parts, viz, a rear transmission case having an opening through its bottom, an engine 100 unit including the crank case having an open bottom, a front gear housing having an opening through its bottom, and having a forwardly extended shelf adjacent its bottom, a pan secured to the lower edges of 105 said three parts closing the openings through their bottoms, a radiator housing fixed to the forwardly projecting shelf of the front gear case, a standard fixed to the said frame behind the engine, a rigid cradle fixed to the radiator housing and to said standard and located in a plane above 110 the engine, and a fuel tank fitted and secured within said cradle over the engine.

6. In a machine of the character specified, a main frame including an engine, a radiator housing fixed to said frame, an upright standard fixed to said frame, said standard having its top portion bent over, and a rigid cradle fixed to and supported by the bent over portion of said standard and by said radiator housing.

In testimony whereof, I hereunto affix my signature.

ROLLIN H. WHITE.
